United States Patent Office

Des. 214,673
Patented July 15, 1969

214,673

COMMODE

John B. Thorn, Lynchburg, and Andre Bus, Altavista, Va., assignors to The Lane Company, Inc., Altavista, Va., a corporation of Virginia

Filed Apr. 10, 1967, Ser. No. 6,608

Term of patent 14 years

Int. Cl. D6—01

U.S. Cl. D33—19

Fig. 1.

Fig. 2.

The rear of the commode is plain and unornamented.

We claim:

The ornamental design for a commode, as shown and described.
